UNITED STATES PATENT OFFICE.

CHARLES H. HYMAN, OF CHICAGO, ILLINOIS.

TOY.

1,348,423.

Specification of Letters Patent. Patented Aug. 3, 1920.

Application filed March 15, 1919. Serial No. 282,904.

To all whom it may concern:

Be it known that I, CHARLES H. HYMAN, a citizen of the United States, residing at Chicago, in the county of Cook and State 5 of Illinois, have invented certain new and useful Improvements in Toys, of which the following is a specification.

This invention relates to toys and is in the nature of a target toy designed to interest 10 and amuse children and stimulate their skill and accuracy of vision and manipulation in projecting a missile at a target.

My invention is illustrated in the accompanying drawing, in which—

Figure 1 is a perspective elevation of the 15 toy; and

Fig. 2 is a top plan view.

Referring to the drawing, 5 designates as 20 an entirety a circular target, preferably made of soft wood or some similar material, and 6 designates a depending handle that is rigid with the target 5 and by which the latter is firmly held in one hand of the child. The target is preferably, and as here shown, 25 provided with a central hole 7, constituting the bull's eye and is also preferably marked on its face with a series of concentric circles bounding annular zones 8, 9, 10, 11 and 12 of different values, as indicated.

30 Detachably secured to the face of the target 5 at diametrical opposite points are a pair of posts 13, these latter preferably having threaded ends which screw into tapped holes in the face of the target so as 35 to render the device readily collapsible for shipment. Directly attached to the outer ends of the posts 13 are the two ends of an elastic propulsion cord 14. 15 designates the missile, in this case shown as of the pointed 40 bullet form, and having a longitudinal kerf 16 at its rear end and by which it may be engaged by the looped or folded end of cord 14.

In the use of the device, the child grasps 45 the target 5 by the handle 6 in one hand, and enters the missile 15 on the cord 14, then retracts the missile, stretching the cord, and aiming at the bull's eye, lets go. If the

shot is perfect, the missile passes through the hole 7, the diameter of the missile being 50 slightly smaller than the diameter of the hole. If the child misses the bull's eye, the pointed end of the missile impinges upon one of the annular zones surrounding the bull's eye, either sticking or leaving its mark 55 of impact in the latter.

I also preferably employ, in addition to the structural features already described, an alarm or signal for indicating when a bull's eye shot has been made. This signal may 60 take the form of a bell 17 which may be removably mounted on the back of the target 5 by means of a post or pin 18, a portion of the bell lying directly behind the bull's eye hole 7. When using the device with the bell 65 attachment, a round missile 15' is preferably employed, to avoid blunting the sharp point of a pointed missile, although the latter may be used if desired.

I claim:

1. A target toy, comprising a target having a hole at its bull's-eye and a series of concentric circles bounding annular zones of different values, a handle rigid with said target, a pair of posts detachably mounted 75 on the face of said target at diametrically opposite points of the latter and normal to the plane of said face, an elastic propulsion cord attached at its ends to the outer ends of said posts, and a missile formed with a narrow slot or kerf for engagement with said cord and adapted to be propelled by the latter against said target.

2. A target toy, comprising a wooden target having a hole at its bull's-eye and a series 85 of concentric circles bounding annular zones of different values, a handle rigid with said target, an elastic propulsion cord connected at its ends to diametrically opposite points of said target, and a missile having a sharp 90 pointed forward end adapted to penetrate and stick in said target and a narrow slot or kerf at its rear end for engagement with said cord.

CHARLES H. HYMAN.
